DE 10223195 12/2003

(Continued)

Primary Examiner — T. Chase Nelson*Assistant Examiner* — Kathleen M Sims(74) *Attorney, Agent, or Firm* — Kenyon & Kenyon LLP(57) **CLAIM**

The ornamental design for a garment drying apparatus, as shown and described.

DESCRIPTION

FIG. 1 is a front elevational view of a garment drying apparatus showing my new design expanded open with poles; FIG. 2 is a rear elevational view thereof;

FIG. 3 is a top plan view thereof;

FIG. 4 is a bottom plan view thereof;

FIG. 5 is a right side view thereof; and,

FIG. 6 is a left side view thereof.

The broken line showing of details in FIGS. 1-6 is included for the purpose of showing environmental portions of the garment drying apparatus and forms no part of the claimed design.
